Harve R. Stuart, Springfield, Ohio, assignor of
one-half to Louis Ilmer, Cortland, N. Y.

Application August 23, 1938, Serial No. 79,513

Term of patent 7 years

To all whom it may concern:

Be it known that I, Harve R. Stuart, a citizen of the United States, residing at Springfield, in the county of Clark and State of Ohio, have invented a new, original, and ornamental Design for a Direction Indicating Signal Controller for Automotive Vehicles, of which the following is a specification, reference being had to the accompanying drawing, forming part thereof.

Figure 1 is a perspective view of a direction indicating signal controller for automotive vehicles, showing my new design and

Figure 2 represents a bottom view of the direction indicating signal controller for automotive vehicles shown in Figure 1.

The handle is fragmentarily shown in the drawing for convenience of illustrating a conventional handle.

I claim:

The ornamental design for a direction indicating signal controller for automotive vehicles, as shown and described.

HARVE R. STUART.
